DESIGN.

C. GRODKOWSKY.

CURTAIN PEDIMENT.

APPLICATION FILED MAY 18, 1916.

49,352.

Patented July 11, 1916.

Inventor

Charles Grodkowsky

By his Attorney Oscar Geier

UNITED STATES PATENT OFFICE.

CHARLES GRODKOWSKY, OF BALTIMORE, MARYLAND.

DESIGN FOR A CURTAIN-PEDIMENT.

49,352.

Specification for Design.

Patented July 11, 1916.

Application filed May 18, 1916. Serial No. 98,461. Term of patent 3½ years.

To all whom it may concern:

Be it known that I, CHARLES GRODKOWSKY, a subject of the Czar of Russia, residing at Baltimore, in the State of Maryland, have invented a new, original, and ornamental Design for a Curtain-Pediment, of which the following is a specification, reference being had to the accompanying drawing, forming part thereof.

The figure is a side elevational view of a curtain pediment showing my new design and illustrating its application to an ordinary curtain.

I claim:—

The ornamental design for a curtain pediment as shown.

CHARLES GRODKOWSKY.

Witnesses:

SINCIA L. FILLER,
LOUIS SYMONOSKI.
